UNITED STATES PATENT OFFICE.

HUGO JOHN, OF ERFURT, GERMANY.

METAL-CUTTING MACHINE.

No. 841,979.

Specification of Letters Patent.

Patented Jan. 22, 1907.

Application filed April 12, 1906. Serial No. 311,376.

To all whom it may concern:

Be it known that I, HUGO JOHN, manufacturer, a subject of the King of Prussia, German Emperor, residing at Erfurt, Kingdom of Prussia, German Empire, have invented certain new and useful Improvements in Metal-Cutting Machines, of which the following is a specification.

My invention relates to a machine for dividing sectioned iron of all kinds by stamping out and cutting out a strip from the work, this machine being chiefly intended for sectioned roller-iron, double T-girders, angle-irons, "bulb iron," U, Z, and T irons. For complicated forms of iron—double T-girders, U, Z, and bulb irons—the separation is effected in two cuts, a left and a right hand cut. For simple forms of iron, such as T and angle irons, the article is separated by one cut.

The machine acts in such manner that when cutting complicated forms of iron the upper cutter cuts first in one and then in the other direction, this being effected owing to the upper cutter being mounted in a balance-beam which can be supported in the frame on the left as well as on the right hand of the upper cutter and is alternately rotatable about a pin on the left and on the right hand sides. The special feature of the machine according to this invention consists, further, in the use of a bottom cutter-holder which is turned through an angle of one hundred and eighty degrees. This bottom cutter-holder, with its bottom cutters, is adjusted in such manner that it rests against the inner flange of the girder to be cut, at least along one-half of the web of the girder. The bottom cutter-holder, rotatable through an angle of one hundred and eighty degrees, during the cutting supports first one and then the other side of the double T-girder to be cut. Owing to this arrangement the girder need not be turned or moved while being cut. It is placed between two parts of lateral cutters placed laterally against the flanges and on the bottom cutter-holder, which is turned under the girder through an angle of one hundred and eighty degrees.

50 The machine can be constructed in such a manner that the withdrawal of the inoperative pivot-pin and the introduction of the operative one for the balance-beam supporting the top cutter are effected simultaneously, so that only one bolt at a time acts as a pivot-pin for the balance-beam supporting the up-

per cutter. Further, the rotation of the bottom cutter-holder can be rendered dependent on the introduction and removal of the pivot-pin of the top cutter balance-beam in such a manner that the upper cutter could cut only in that direction in which the girder is supported by the bottom cutter-holder.

The machine can be further arranged so that the two pairs of lateral cutters are simultaneously and uniformly pressed against the flanges of the double T-girder to be cut, and the holders of the lateral cutters can be arranged on paths inclined toward the working opening in order to enable the top cutter to cut freely even girders of small cross-section. The driving-gear for the machine can also be provided with such an arrangement that the driving mechanism would be thrown into gear only when one of the pivot-pins of the top cutter balance-beam is in the operative position and the other in inoperative position and also the bottom cutter-holder is in one or the other of its end positions. It is also advantageous not only to balance the balance-beam for the upper cutter-holder, but to overbalance it in order that the axis of the pivot-pin to be introduced should always coincide with the perforation in the balance-beam. Finally, the machine is provided with a stripping device which after the first cut has been made (before the throwing of the machine into gear for the second cut) effects the stripping off of the work and also protects the upper cutter from injury during the introduction of the work.

A construction of the machine according to this invention is illustrated, by way of example, in the accompanying drawings.

Figure 1 shows the same in front elevation and Fig. 2 in plan. Fig. 3 is a section chiefly on the broken line A B of Fig. 1. Fig. 4 is a horizontal section on C D. Figs. 5 and 6 show the stripping-off device in front and side elevations. Figs. 7 to 10 show diagrammatically the working of the machine during cutting in one or in the other direction. Figs. 11 and 12 show the action of the lateral cutters guided on inclined planes or paths when cutting small girders.

The construction of the machine is as follows:

The body of the machine constituted by suitable plates 1 and 2, supported by brackets 3 and 4, is provided at the bottom with a working opening. The tools comprise a rotatable bottom cutter-holder 5, with bottom

cutters 6 and 7, secured to their seat by means of screws and pins, two lateral cutters 14, and an upper cutter 25, cutting between the lateral cutters and the bottom cutters.

5 The bottom cutter-holder 5 is adjustably mounted on a rotatable plate 8 and is held fast in its position by means of two screws 8^a and 8^b or by some other means. The plate 8 rests on the walls of the frame and rotates 10 about a central pin 9, (see Fig. 3,) secured by a pin 10 to the frame-body 12. The plate 8 is provided on the largest portion of its circumference with teeth 11, which serve to rotate the said plate 8 by means of a toothed 15 rack 45 in the manner hereinafter described. The pin 9 rests in a part 12, filling up the bottom of the frame-body 12 and screwed to it. The bottom cutter-holder is adjusted to suit the dimensions of the girder to be cut. The 20 diameter of the half-circle which it describes is in the construction shown in Fig. 1 about equal to the inside depth of the I-girder. After the first cut has been effected the bottom cutter-holder is turned through an angle 25 of one hundred and eighty degrees before it makes the second cut.

The lateral cutter group, arranged so as to be movable on inclined paths, comprises two lateral cutter-holders 13, each of which receives 30 a pair of lateral cutters 14. The two lateral cutter-holders are guided at the top and at the bottom in corresponding recesses of the two walls 1 and 2 of the frame and at the bottom by means of parts 15, introduced 35 between the walls of the frame. The guiding at both sides is effected by means of plates 1^a and 2^a, riveted to the central walls. The back surface of the lateral cutter-holders are provided with a through-groove 16, with 40 which engage correspondingly-shaped heads of the two screw-threaded spindles 17. These screw-threaded spindles engage with tapped holes in two transverse pins 18, passing through the main body and screwed fast to 45 the same. On the grooved smooth end of the spindles 17 are mounted toothed wheels 19, which are prevented from laterally shifting by means of suitable bearings 19^a. With the wheels 19 engage toothed wheels 20. The 50 connection of the two toothed-wheel systems is effected by means of a spindle 21, which passes laterally of the frame-wall 2, parallel to the same, and is guided in bearings 22. One of the spindles 17 is provided 55 with a right-hand screw-thread and the other with a left-hand screw-thread. The spindle 21 is rotated by means of a crank-handle 23, whereby the screw-spindles 17 are shifted relatively to each other and the cutter systems 60 are simultaneously brought nearer to or moved farther away—that is to say, adjusted—to suit the height of the section to be cut.

The upper cutter is the only power-driven cutting part of the machine and serves for 65 cutting out a strip from the work—for in-

stance, from the double T-girder illustrated. The upper cutter 25 is mounted on the adjustable upper cutter-holder 24. Its upper portion 25^a is inclosed in the upper cutter-holder in such manner that the cutting-plate 70 25^b projects downward. The upper cutter is held fast in its seat by means of a bolt 26. The upper cutter-holder 24 has the shape of a balance-beam. It tapers toward its two ends, and at each end it is provided with a perforation for receiving an oscillation-pin 27. As stated in the introduction, the upper cutter-holder must be rotatable about one pin 27 during the cutting of the upper cutter in one direction and during the cutting in the 75 other direction about the other pin 27. The upper cutter-holder must therefore execute an oscillating movement about one pin, and during that time the other one must be withdrawn from its perforation. In order that 80 the upper cutter-holder on its return to the upper end position, Fig. 1, may find again its proper position, the pin or bolt is made so that it cannot be withdrawn altogether; but the material of the upper cutter-holder 24, 85 situated over the short end of the bolt 27, remaining inside is cut so as to form a groove 29. By this means the upper holder, which receives its working pressure from above, is free to move downward, and at the same 90 time the proper position of the cutter and the material to be cut is insured. The bolts 27 are guided and supported each in a socket 30 and in a bearing-ring 31, secured to the frame-walls in a suitable manner. 100

In order that a bolt 27 may act as a pivot-pin for the upper cutter-holder and that the other may be simultaneously withdrawn and in order to obtain this action alternately, the following arrangement has been provided. 105

The bolts are connected by rods constructed of two bell-crank levers 28 and a rod 32, connecting the same, together with hinge-pins 32^a. On a bearing 33, screwed to the walls of the frame, rests the left-hand bell-crank lever and pivots about the pin 33^a. The longer end of each bell-crank lever is formed into an eye 28^a and engages with a recess 27^a of the bolt 27. In order to make this possible, the socket 30 is provided with 110 a slot 30^a, Fig. 3, through which can pass the bell-crank lever 28. The right-hand bell-crank lever 28 rests on a bearing 35. In this way when one bolt 27 is withdrawn the other bolt 27 is introduced into the upper cutter-holder and the bearing-ring 31. In order to enable this adjustment to be effected by hand, the following mechanism is provided: The right-hand bell-crank lever 28 rests on the bearing 35 and is secured to the vertical 115 spindle 36. The bearing 35 is screwed to the frame and serves as a bottom guide 35^a for the spindle 36. The bearing 35 is screwed to the frame and serves as a bottom guide 35^a for the spindle 36. The upper guide for the same is constituted by the bearing 37, also 120 screwed to the wall 1 of the frame. The col- 125 130

lar 38 below the guide of the spindle on the bearing 35 and a disk 39 at the upper end of the spindle 36 prevent the latter from moving longitudinally. To the bottom end of the spindle 36 is secured a bevel-wheel 40. At right angles to the spindle 36 is inserted into the projection 35^b of the bearing 35 a pin 41, on which rotates a bevel-wheel 42, to the hub of which is secured a double-armed lever 43. A nut 41^a of the pin protects the lever and toothed wheel against movement. A weight 43^a is secured to the end of the upper arm of the lever 43 by means of a bolt 43^b, provided with a collar. The projecting end of this bolt is formed into a handle 43^c.

The movement of the lever 43 in the direction of the arrow toward the right—that is to say, from the left-hand end position shown in Fig. 1 into the dotted position x y—causes the spindle 36 to turn, and therefore the bell-crank lever 28 to turn correspondingly, and the two bolts 27 to move. During that time the weight 43^a causes the lever 43 to remain in its end position until the action of the weight 25 is neutralized by the pull on the handle 43^c.

The device described, which brings about positive movement of the bolts 27 toward each other, can be connected to a device which brings about the rotation of the bottom cutter-holder 5 in such manner that when the left-hand bolt 27 is introduced as a pivot-pin for the upper cutter-holder 24 the bottom cutter-holder 5 is moved into its left-hand end position. On the contrary, when the right-hand bolt 27 is introduced and the left-hand bolt 27 thus removed the cutter-holder 5 is turned through an angle of one hundred and eighty degrees into its right-hand end position. In order to effect that, one end 40 of a link 44 is connected by a bolt and nut 44^a to the bottom arm of the lever 43, while the other end is connected to a toothed rack 45 by means of a bolt 44^b. The teeth of the toothed rack engage with the teeth 11 on the rotatable plate 8. The under face of the toothed rack 45 is supported and guided by an angle-bar 46 and at the back wall and at the upper surface by angular guides 47, screwed to the said bar, Fig. 3. In this way 50 simultaneously with the movement of the bolts 27 the rotation of the plate 8 takes place, together with that of the bottom cutter-holder 5 resting upon it. The rate of transmission of the two bevel-wheels 40 and 42 is chosen so that each movement of the lever 43 from one end position to the other causes one of the bolts to be withdrawn and the other to be introduced and the bottom cutter-holder to be turned exactly through 55 an angle of one hundred and eighty degrees about its vertical axis. Two stops 47^a, against which the ends of the tooth-rack strike, limit the position of the bolts 27 and the position of the bottom cutter-holder 5.

65 Instead of limiting the rotation of the bottom

cutter-holder in the above way any other means could be chosen. For instance, the stops could be secured to the plate 8, and so on. In this way the bottom cutters are adjusted in their two end positions in such a 70 manner that the upper cutter can safely be introduced into and pass through the space between the bottom cutters.

In order that the upper cutter-holder 24 may always rest against the bottom surface 75 of its groove 29, even when the bolts 27 are withdrawn—that is to say, in order to enable the bolts to be introduced again into their right position—the cutter-holder 24 is not only balanced, but overbalanced. In this 80 way the working parts are relieved from the raising operation and the introduction and removal of the bolts are insured even when, owing to the wear of the working parts, there is backlash, and therefore a loss of 85 stroke in the upper cutter-holder. This overbalancing is effected in the following manner: About a bolt 48^b, let into the back frame-wall 2, oscillates a lever 48. To its front end is joined by a bolt and nut 48^a a 90 link 49, the bottom end of which engages a bolt 49^a, screwed into the upper cutter-holder. The back frame-wall is for that purpose cut out upward to such an extent (Fig. 1 dotted) that the bolt 49^a is situated in 95 the working opening—that is to say, can freely participate in the movement of the upper cutter-holder. On the front end of the lever 48 there acts a pressure-spring 50, threaded upon the guide-rod 51. The latter 100 is provided at the bottom with a collar 51^a and below the same with a hinge part 51^b, engaging the lever 48 by means of a bolt and nut 51^c. An abutment 52 of the spring 50, which at the same time forms a guide for the 105 rod, is screwed at the top to the wall of the frame. In that way the spring 50 exercises a pressure on the collar 51^a, swings the front end of the lever 48 upward, and then pulls the upper cutter-holder 24 upward, when 110 the latter is not exposed to any downward pressure by the driving-gear.

For carrying out the operation a suitable force is required which acts vertically on the center of the upper cutter-holder, the working stroke being adjusted to suit the largest sectional dimensions of the iron to be cut. 115

The machine can be provided with any desired hand or power drive. This drive does not form the subject of this invention. 120 In the drawings the machine is shown with the ratchet-gear described in the German Patents Nos. 119,653 and 119,882, (the so-called "John's oscillating lever-gear.") This gear is provided with the pressure-part-releasing device applied for in the German application, Serial No. 40,993 of the 23d September, 1905, corresponding to the United States application for ratchet feeding mechanism, filed November 13, 1905, 130

Serial No. 287,133. In the construction illustrated this release is rendered dependent on the levers 43 in such manner that the throwing into gear of the pressure part *k*, Fig. 1, is possible only in the two end positions of the lever 43. To that end the disk 39 secured to the spindle 36 is provided with two recesses 39^a and 39^b, while the hand-lever *h*, (marked 19 in application Serial No. 40,993,) effecting the throwing into gear, carries a latch *f* secured to it. In each of the two end positions of the lever 43 one of the recesses 39^a or 39^b is in such a position relatively to the latch *f* that it can freely engage with it, and therefore the pressure part *k* can be brought into gear. In any other position of the lever 43, the throwing into gear is rendered impossible, owing to the latch *f* coming in contact with the non-slotted portion of the disk 39, so that the movement of the hand-lever *h*, and therefore the throwing into gear of the power-drive, becomes impossible. The coöperation of the engaging lever *h* and slotted disk 39 insures the correct position of the oscillating bolts and of the bottom cutter-holder and also insures safety of the attendants of the machine.

The release of the pressure part *k*—that is to say, the stopping of the working parts—is automatically brought about in the upper position of the eccentric, and therefore also of the upper cutter, as described in the application Serial No. 40,993. The throwing into gear for each cut is effected by a rocking of the lever *h* from the left to the right hand side.

For the double purpose, first, of holding fast the work partly cut during the removal, (ascent of the upper cutter,) and, secondly, of protecting the upper cutter from injury or breakage during the introduction of the work to be cut there is provided a stripping-off device, Figs. 5 and 6.

The stripping-off device 53 is bent at its bottom end 53^a in the shape of a hook in order to guide downward and into the cutter system the work moved in the direction of the working opening, but perhaps held slightly too high. The stripping-off device is rotatably suspended by means of the bolt 53^b in the bearing 54, secured to the wall of the frame, so that it can be raised upward when the working opening (for instance, during the change of tools) is to be clear or when it is not to be used, (for instance, when cutting such irons as have to be cut in one operation.) From its bottom position the stripping-off device cannot be forced in the direction toward the upper cutter, as it would strike in the stripping-off bearing against a stop-surface 54^a.

The working of the machine is as follows: Assuming that it is desired to cut a double-T girder and that the parts of the machine are

in the position shown in Fig. 1, the bottom cutter-holder is arranged and fixed to suit the inside height of the girder-section. The girder to be cut is pushed into the working opening and the lateral cutters are brought, by means of the crank up to the flange. The pressure part *k* is thrown into gear, whereupon the left-hand cut is at once effected in the direction of the arrow, Figs. 7 and 8, and up to the point of the same, and the upper cutter is positively returned along the same path into its upper end position, Fig. 7, where it will be stopped by the automatic pressure-part-disengaging gear. The weight-lever 43 is then thrown from its left-hand position, Fig. 1, toward the right, whereby the left-hand pivot-pin 27 is withdrawn and the right-hand one introduced, and the bottom cutter-holder is turned through an angle of one hundred and eighty degrees—that is to say, from its left-hand end position into the right-hand end position, Fig. 9. The second cut is thus prepared, and it is only necessary to again throw into gear in order to effect it, Fig. 10. This throwing into gear is rendered possible, as the latch *f* on the lever *h* can engage with the slot 39^b of the disk 39.

The shavings or waste produced during the cutting fall between the walls of the frame into a pit arranged under the machine. The path for it is rendered free by corresponding holes in the insertion parts.

For cutting I, U, Z, and "bulb" irons the process is the same as above described.

The cutting of T and angle irons is effected only on one desired side, as they can be cut in one operation.

For cutting I, U, Z, and bulb irons of smaller cross-section a small upper cutter and a shorter bottom cutter-holder are put in, the lateral cutters being adjusted for all kinds and sizes of iron which the machine can cut at all. In order to make it possible to cut smaller girders with shorter bottom cutter-holders and smaller upper cutters, while keeping the same lateral cutters 14, the lateral cutter-holders are arranged on planes or paths inclined toward the center of the work, so as to enable a free cut to be effected and so that the lateral cutter-holders are not in the way of the upper cutter-holder. Figs. 11 and 12 illustrate the position of the lateral cutters for smaller and shorter bottom cutter-holders and the movement of the upper cutter for the said position.

What I claim is—

1. In a machine of the class described, the combination with a movable cutter-head provided with cutting means to operate upon different portions of the stock, a movable shearing device, and means coöperative with the head and shearing device for causing the movement of the latter to bring it into position to coöperate with said cutting means on each action of the said head.

2. In a machine of the class set forth, the combination with an oscillatory head carrying cutting means, coöperating movable shearing devices, and means coöperative with the head and shearing device for causing a movement of one on the action of the other. 5
3. In a machine of the class described, the combination with a cutter-head having cutting means and two distinct stages of operation, a shearing device, and connections between the cutting-head and shearing device for causing the movement of the shearing device to bring it into position to coöperate with said cutting means on each stage of the 10 operation of the cutter-head. 15
4. In a machine of the class set forth, the combination of an oscillatory cutter-head, pressure mechanism, and coöperative shearing devices, the said cutter-head being movable about a plurality of pivots. 20
5. In a machine of the class set forth, the combination of an oscillatory cutter-head, pressure mechanism, and coöperative shearing devices, the said cutter-head being movable about a plurality of detachable pivots. 25
6. In a machine of the class set forth, the combination of an oscillatory cutter-head, pressure mechanism, and coöperative shearing devices, the said cutter-head being alternately movable about a plurality of pivots. 30
7. In a machine of the class set forth, the combination of an oscillatory cutter-head, pressure mechanism, and coöperative shearing devices, the said cutter-head being movable about a plurality of alternately-detachable pivots. 35
8. In a machine of the class set forth, the combination of a cutter-head, pressure mechanism, coöperative shearing devices, the said cutter-head being movable about a plurality of pivots, one of said pivots adapted to be withdrawn while the other forms a pivot-pin for the said cutter. 40
9. In a machine of the class set forth, the combination of a cutter-head, pressure mechanism, coöperative shearing devices, the said cutter-head being movable about a plurality of pivots, and connecting means for engaging the said pivots and alternately changing the 45 bearing of the cutter-head. 50
10. In a machine of the class set forth, the combination of a cutter-head, pressure mechanism, coöperative shearing devices, the said cutter-head being rotatable about a plurality of slotted pivots, and a connecting member having terminally-disposed bell-crank levers adapted to engage the slots in said pivots and alternately change the bearing of the 55 cutter-head. 60
11. In a machine of the class set forth, the combination with a cutter-head, pressure mechanism and coöperative shearing devices, of means for automatically controlling the return of said cutter-head comprising a 65 pressure-spring and a weighted lever. 65
12. In a machine of the class set forth, the combination of a cutter-head, pressure mechanism and coöperative shearing devices, the said cutter-head being rotatable about a plurality of pivots and provided with a guide-groove extending upwardly and merging at the bottom into the perforations of said pivot-pin. 70
13. In a machine of the class set forth, the combination with an oscillatory head carrying a cutter, of shearing devices comprising simultaneously-adjustable side members, and a movable and adjustable bottom member, the latter adapted to form a cutting-abutment. 75
14. In a machine of the class set forth, the combination with an oscillatory head carrying a cutter, of shearing devices comprising adjustable side members, and a movable and adjustable bottom member, the latter being 80 of a width at least equal to one-half of the inside depth of the girder and adapted to alternately form a cutting-abutment. 85
15. In a machine of the class set forth, the combination of a cutter-head, pressure mechanism and a movable shearing device, the said cutter-head being rotatable about a plurality of pivots, a member connecting said pivot-points, a rotary shaft having a toothed gear adapted to coöperate with said connecting member, and a weighted lever geared to said shaft and connected to the shearing device. 90
16. In a machine of the class set forth, the combination of a cutter-head, pressure mechanism and a rotatable shearing device, the said cutter-head being rotatable about a plurality of pivot-points, a member connecting said pivot-points, a rotary shaft having a toothed gear adapted to coöperate with said connecting member, a weighted lever geared to said shaft and connected to the shearing device, and stops for limiting the oscillation of the said lever. 95
17. In a machine of the class set forth, the combination with an oscillatory cutter-head, of a rotatable shearing device and opposing holders mounted on screw-threaded spindles and carrying cutters, pinions on the respective spindles, and a power-transmitting shaft 100 with correspondingly-engaging pinions adapted to simultaneously adjust the cutters laterally. 110
18. In a machine of the class set forth, the combination with an oscillatory cutter-head, of a rotatable shearing device and lateral cutters, and inclined means on which the cutters slide. 115
19. In a machine of the class set forth, the combination with an oscillatory cutter-head, of a rotatable shearing device and lateral cutters, and inwardly-inclined means on which the cutters slide. 120
20. In a machine of the class set forth, the combination of an oscillatory cutter-head, of 125 a pressure-spring and a weighted lever. 130

- a rotatable shearing device and opposing 5 holders mounted on screw-threaded spindles and carrying cutters, pinions on the respective spindles, inclined blocks, and a power-
5 transmitting shaft engaging said pinions thereby adjusting them simultaneously, the holders sliding on the inclined blocks.
21. In a machine of the class set forth, the 10 combination with an oscillatory cutter, co- operative rotatable cutters, and pressure mechanism, of a spindle in operative relation therewith and adapted to be controlled by the operation of the pressure mechanism.
22. In a machine of the class set forth, the 15 combination with an oscillatory cutter, co- operative rotatable cutters and pressure mechanism, of a spindle carrying a notched disk, a locking projection, levers connecting the pressure mechanism with the said projec-
20 tion and adapted to be simultaneously oper- ated with the pressure mechanism.
23. In a machine of the class set forth, the combination of an oscillatory head having a
- cutter, of a plurality of shearing cutters, and a hinged stripping-off device having an up-
25 turned terminal and adapted to support the work when the upper cutter is removed.
24. In a machine of the class set forth, the 30 combination with an oscillatory head carry- ing a cutter, of a rotatable shearing device and means for causing the action of one upon the movement of the other.
25. In a machine of the class set forth, the 35 combination with an oscillatory head carry- ing a cutter, of a rotatable and adjustable shearing device and means for causing the action of one upon the movement of the other.
- In testimony whereof I have hereunto set my hand in presence of two subscribing wit-
nesses.

HUGO JOHN.
